UNITED STATES PATENT OFFICE.

JOHN V. PALMER, OF PITTSBURGH, PENNSYLVANIA.

APPAREL COLLAR.

Application filed October 22, 1921. Serial No. 509,504.

To all whom it may concern:

Be it known that I, JOHN V. PALMER, a citizen of the United States, residing at Pittsburgh, in the county of Allegheny and

5 State of Pennsylvania, have invented certain new and useful Improvements in Apparel Collars, of which the following is a specification.

This invention relates to apparel collars 10 and more particularly to collars of the turn-over type.

One of the primary objects of the present invention is to provide a collar of the turn-over type which will afford ample ventilation about the neck of the wearer by providing for the free circulation of air substantially entirely around the neck and practically to the same extent as though the collar were spaced considerably from the neck 20 instead of tightly fitting the same, although the collar embodying the invention is adapted to snugly surround and fit the neck in the same manner as any ordinary collar of this type.

25 Another object of the invention is to so construct the collar that while it will afford ample ventilation about the neck of the wearer, it will not possess any features rendering it uncomfortable to wear nor will 30 any of the features of construction embraced in the invention interfere in any way with the application and tying of the ordinary necktie.

It is well-known to wearers of turn-over 35 collars of the starched kind that in summer time the collar fold at the front becomes saturated with perspiration and soon collapses thereby becoming unsightly. It is therefore another important object of the 40 present invention to provide means whereby to avoid the collapse of the fold of such a collar under the conditions stated so that even should the collar at this point become saturated with perspiration, it will maintain 45 its original form and attractive appearance.

In the accompanying drawings:

Figure 1 is a view in elevation of a collar embodying the present invention, the view 50 being taken looking at the inner side of the collar.

Figure 2 is a vertical transverse sectional view on the line 2-2 of Figure 1.

Figure 3 is a similar view on the line 3-3 55 of Figure 1.

Figure 4 is a view similar to Figure 1

showing one end of the collar, the folds being spread open and the view illustrating the means provided for preventing collapse of the front of the collar.

60 The collar embodying the invention comprises, as usual, inner and outer folds which are indicated by the numerals 1 and 2 respectively. The outer fold 2 may be of any desired marginal contour and in fact this 65 will vary in different styles of collars. Also this fold may have any desired dimension as is usual. Unlike the outer fold of the ordinary collar however, the collar of the present invention has its said fold provided at a point midway between its ends with a buttonhole 3 adapting this fold to be buttoned to the back button of the collar band of the shirt. The inner fold 1 of the collar is provided with the usual terminal 70 tab portions 4 which are designed to be overlapped when the collar is buttoned about the neck, and these tab portions are provided with a buttonhole 5 to receive the front button of the neck band of the shirt. 75

In order to provide for circulation of air about the neck substantially entirely around the back and sides, the inner fold 1 of the collar is cut away approximately throughout its entire length as indicated by the 80 numeral 6. In other words, this fold, between the tab portions 4 is substantially omitted or generally speaking is greatly reduced in height so that throughout nearly its intermediate length it is very narrow as indicated by the numeral 7. As a result of this construction, while the outer fold 2 is buttoned to the neck band of the shirt at the rear, practically all of the remaining area of the said outer fold is so spaced from the 85 neck of the wearer of the collar as to provide for the free circulation of air around the back and sides of the neck. At the same time the portion 7 of this fold is of sufficient depth to provide for a smooth and snug 90 fit of the upper edge or rim of the collar against the neck so that when worn the collar will have identically the appearance of the ordinary turn-over collar.

95 The tab portions 4 and the portions of the 105 fold 1 immediately inwardly thereof are of the usual depth so as to properly support the front portion of the collar when worn and to present a smooth surface to the throat of the wearer but in order to provide for ventilation of the neck at the front, these portions of the said fold 1 are provided each 110

with a ventilating opening indicated by the numeral 8, this opening being located between the projecting tab portions 4 and the ends of the cut-away portion 6 of the said fold 1. Also, preferably, these openings are located only a short distance below the crease which connects the upper portions of the two folds 1 and 2. As before stated it is one of the objects of the present invention to provide means for preventing collapse of the front of the collar when the same becomes saturated with perspiration and in order that this may be accomplished, a reinforcing ply of heavy cloth material indicated by the numeral 9, is stitched as at 10 along one longitudinal edge to the inner side of the inner fold 1 of the collar and extends across the crease line between the folds 1 and 2 as best shown in Figure 4 of the drawings. The other edges of this ply or strip are preferably left unattached and when the collar is laundered the said ply 9 is creased longitudinally at the time the crease is formed in the collar between the folds 1 and 2, so that the 25 ply 9 provides a reinforcement within the crease at the ends of the collar immediately inwardly of the tab portions 4. This ply 9 being of heavy cloth such for example as duck, constitutes a stiffening medium and

serves to support the folds 1 and 2 at their 30 uniting crease even though the folds become saturated with perspiration.

Having thus described the invention, what is claimed as new is:

1. A turn-over apparel collar comprising inner and outer folds and a connecting crease, and a reinforcing ply disposed against the inner sides of the folds and united along one edge to the inner fold, the ply being creased within the crease between 40 the folds and being free from attachment at its opposite edge to either fold.

2. A turn-over apparel collar comprising inner and outer folds and a connecting crease, and a reinforcing means for the 45 front ends of the folds comprising strips disposed against the inner sides of the folds and united each at one longitudinal edge to the inner fold in spaced relation to the crease between the folds, the said strip being creased within said crease between the folds and having its other longitudinal edge free from attachment to either fold, the inner fold being provided in each of its end portions with a ventilating opening in juxtaposition to the respective reinforcing strip.

In testimony whereof I affix my signature.
JOHN V. PALMER. [L. s.]
